DESIGN FOR A BOTTLE

Wilbur A. Holtz, Toledo, Ohio, assignor to Owens-Illinois Glass Company, Toledo, Ohio, a corporation of Ohio

Application March 19, 1937, Serial No. 68,283

Term of patent 14 years

To all whom it may concern:

Be it known that I, Wilbur A. Holtz, a citizen of the United States, residing at Toledo, in the county of Lucas and State of Ohio, have invented a new, original, and ornamental Design for a Bottle, of which the following is a specification, reference being had to the accompanying drawing forming a part thereof.

In the drawing:

Fig. 1 is a side elevational view of a bottle showing my new design.

Fig. 2 is a top plan view thereof.

I claim:

The ornamental design for a bottle substantially as shown.

WILBUR A. HOLTZ.
